UNITED STATES PATENT OFFICE

ALFRED M. MARTIN, OF CHICAGO, ILLINOIS

PARTITION SHEET FOR BINDERS

Application filed May 25, 1929. Serial No. 365,853.

These improvements relate to what are known as partition sheets or division sheets for loose-leaf binders.

My Patent No. 1,269,479 of June 11, 1918, on loose-leaf binders shows a type of loose-leaf binder with which the present partition sheet is peculiarly advantageous. In that patent Figs. 8 and 9 illustrate a form of partition sheet described therein as an indexed leaf for separating the account leaves.

The "account leaves" referred to in said patent are the sheets or cards on which the record is kept. They are of various sizes and are usually of strong paper stock of ordinary thickness. Their depth (from top to bottom) is such that they may be applied to the binder prongs in overlapped relation with a narrow portion of each card exposed, thus forming a series of such cards from top to bottom of the binder. Such overlapping of the cards causes the thickness of the series to build up gradually in the direction in which the cards or sheets are applied, reaching its maximum where there is a maximum of such cards overlapping each other, the thickness then diminishing toward the opposite end of the series. Ordinarily the greatest thickness of the series develops in the central portion, measuring from top to bottom.

A single binder may contain a large number of such series of overlapped sheets, say twenty-five or more. With the ordinary flat division or partition sheets between these respective series the book or binder device may be filled solidly throughout the middle portion thereof while at the top and bottom portions there is considerable free space between the covers. This arises from the fact that at the very top and at the very bottom of the device there may be only say twenty-five of the cards between the two outer covers, while at the same time there may be in the middle two hundred and fifty or more of such cards between the opposed covers.

My Patent No. 1,663,017 of March 20, 1928, entitled Partition sheets for loose-leaf devices illustrates, describes and claims another form of partition sheet in which the effective thickening of the upper and lower portions of the sheets is accomplished by embossing

in various ways sheet material of uniform thickness.

The main object of the present improvements, like that of the device of Figs. 8 and 9 of my first-mentioned patent and the device of my secondly-mentioned patent, is to provide a division or partition sheet for such uses which will occupy space between adjacent series of the overlapped cards, preferably at both the top and bottom portions of the overlapping series, whereby each series will be maintained more nearly flat when the book is opened and therefore be more free of the upwardly bulging effect of the middle portion of the series, with certain advantages in practice such as a more free movement of the cards on the binder prongs, (the cards being relieved of a certain objectionable binding thereon due to the curvature of the series as pointed out), and since the cards or sheets or "account leaves" lie more approximately flat, the making of notations thereon is facilitated, and, further, one or several complete series of record cards or sheets may be moved bodily or en masse from one side of the book to the other more freely and more easily.

In this connection it may be mentioned that the maintenance of such a flat surface at the top of the series is of particular advantage in the act of writing on the upper cards since otherwise this upper portion of the series would slope downward and away from the writer. Such a slope may be to quite a great extent; for instance there may be a difference of more than an inch and a half between the thickness at the middle and at the ends in a binder designed for two-inch capacity.

The present improvements have for one specific object the provision of material which may be made as a long web and then cut into the desired substantially rectangular shape, whereby the cost of production of the device may be reduced. Another object is to provide a sheet which is substantially of even and regular contour throughout whereby certain disadvantages arising from projecting parts are substantially avoided. Another object is to provide a sheet which is substan-

ally flat and of a continuous surface throughout at least one of the face surfaces thereof, to provide a flat writing or rest surface for record sheets thereon. There are certain advantages, too, in a homogeneous and substantially uniform construction, partly residing in general satisfaction to the user and which is of commercial importance. Other objects and advantages will appear herein-after.

In the drawing Figure 1 is a perspective view showing the normally lower face surface of my improved partition sheet, in a preferred embodiment;

Fig. 2 is an enlarged fragmentary and sectional view, as on the line 2-2 of Fig. 1, the sheet being turned over, however, as by swinging it on the edge 13;

Fig. 3 is a perspective view showing modifications; and

Fig. 4 is a fragmentary section on the line 4-4 of Fig. 3, the sheet, however, being swung around as in Fig. 2.

The partition sheet 10 of Fig. 1 has an upper edge 11, a lower edge 12, an inner edge 13, and an outer edge 14 defining a substantially rectangular shape for the sheet in face view. Sometimes the corners of such sheets are rounded. Along the edge 13 is a row of perforations 15 adapted to receive the binder prongs and constituting means for holding the sheet in the binder. It is to be understood that the cards, sheets or "account leaves" on which the records are kept are similarly punched with holes to receive the impaling prongs.

As shown by Fig. 2 the middle portion 16 of the sheet is flat, of substantially uniform thickness, and thin. This portion 16 may have the thickness of ordinary partition sheets. From this middle portion 16 the upper portion 17 and the lower portion 18 gradually increase in thickness toward the top and bottom edges 11 and 12 respectively 45 whereby the sheet is substantially thick at or approximately at these upper and lower edges. The left hand end of Fig. 4 shows that by rounding or some other configurations given to an edge portion as 12 the thickness in question may be somewhat removed from the exact edge, although the desired object would still be attained, and for the desired effects the thickening should extend substantially as far as does the superposed series 55 of record cards or sheets.

Fig. 2 shows that the normally upper surface 20 of the sheet 10 is flat. According to the preferred construction that surface 20 is continuous and without any projections or depressions. That surface is normally immediately under a series of record cards or sheets when the binder is open and lying on a table top or the like and the division sheet is on the right-hand side of the binder. The operator works on that right-hand side. Fig.

1 therefore shows the normally lower face of the sheet, which is true also of Fig. 3. The flat and even surface 20 provides that writing may advantageously be done upon the superposed record cards or sheets and without such interference as would result from an uneven surface. Such interference would be appreciated by the user chiefly at the upper and lower portions respectively of the series of record sheets, at which places the number of such record sheets may be only one or several of them in overlapped relation.

The gradually thickening portions 17 and 18 of Figs. 1 and 2 are provided at intervals between the inner edge 13 and the outer edge 14 with a plurality or series of grooves, recesses or depressions 21 extending from the edges 11 and 12 respectively toward the middle portion 16. These recesses 21 are preferably substantially narrow whereby the intervening spaces 22 are substantially wide whereby the sheet as a whole on the face surface viewed in Fig. 1 is more nearly continuous and not pronouncedly broken so far as general effects are concerned. Stated otherwise, the breaks in the continuity of the facing surface having the recesses are substantially narrow.

The recesses 21, illustrated for the most part in Fig. 1, are substantially rectangular trough-like depressions, but at 24 I have shown one of them rounded and at 25 one of them V-shaped, indicating that these depressions may be of various shapes or contours.

The depressions as 21, 24 and 25 constitute means for rendering the upper and lower relatively heavy portions 17 and 18 more flexible, especially whereby such sheets may flex or bow after the manner of the leaves of an ordinary book when the edge portion at 13 is held in the binder.

The depressions or recesses 21 are shown by Fig. 2 as being of such limited extent (or depth as viewed in Fig. 1) that the upper and lower portions 17 and 18 are somewhat thicker at the bottom of the recesses respectively than is the material at the middle portion 16. This provision is made to strengthen the construction against tearing or breaking where the recesses emerge at the upper and lower edges 11 and 12.

The recesses as 21, 24 and 25 are preferably directed in lines parallel to each other and to the side edges 13 and 14, and preferably also whereby recesses in the upper portion are directed toward corresponding recesses in the lower portion. The sheet as a whole will flex more readily on the lines of these recesses and the flexure of the sheet as a whole will be more uniform if the recesses be so directed.

Probably the most advantageous material for such flexible sheets is paper although the invention is not limited thereto. Among the advantages of paper for the article are that

the material for the device may be made in sheets or in strips according to practices well understood in the paper-making art. To this end rollers would be provided to give the sheet the desired configuration, one roller being cylindrical and the coating one having a shape converse to that of the lower face surface in Fig. 2, with projections arranged on the periphery thereof corresponding to the recesses as 21, or as 24 or 25, as the case may be. The web of material could be wide enough to produce several of the division sheets in end-to-end arrangement across the web, and as the web could be made continuously it would be only a matter of slitting longitudinally and cutting transversely as the web finally issues from the rolls to produce the article complete except for such punching of holes and rounding of corners as may be desired.

Such paper or other fibrous material may be reinforced along an edge or edges by any appropriate form of binding. For this purpose the preferred binding is such as would be applied in liquid form, as by dipping the edge portion of the sheet into the liquid, the liquid penetrating among the fibers of the material and finally hardening. A cellulose compound would be suitable. Such a binding is shown by stippling at 27, 28, 29 and 30.

A feature of advantage is that the holes 15 throughout the portions 17 and 18 are through thicker stock than as usual, and the greater strength thus provided is at places respectively on the sheet where it is proportionately most needed, the greatest need being at the extreme top and bottom of the line of holes.

The device may be made also by taking a sheet of such loosely woven or coarser-texture fibrous material as blotting paper, of the required thickness, and pressing it between dies in a hydraulic press, with moisture and/or heat if preferred, according to the characteristics of the article desired or those of the material used.

Turning to Figs. 3 and 4 I shall describe merely the departures thereof from the device of Figs. 1 and 2.

First, there are no means shown in Figs. 3 and 4 for rendering the thicker portions 30 and 31 more flexible, this construction contemplating the use of material which is sufficiently flexible otherwise, for example paper stock not as tightly rolled or pressed as is contemplated for the device of Fig. 1, or a composition of other substances, for example one including rubber. At 30a and 31a I have shown the upper and lower face surfaces of the sheet parallel, to a small extent, thus avoiding an acute angle at the extreme edge more likely to fray and giving the top and bottom edges a somewhat different "feel" when the leaves are handled in the book. I have also shown the lower edge 32 rounded, which may avoid some fraying or raggedness

at the edge due to wear. The binding feature shown at 27, 28, 29 and 30 of Fig. 1 may be used with the device of Fig. 3, at one or more edge portions as preferred.

If the device were made with only one thickened portion, as 17 or 30, leaving the rest of the sheet thin and uniform like the middle part 16, advantageous results could be had by inserting the sheets in the binder with the thickened portion of one sheet at the top and of the next sheet at the bottom and thus reversing and alternating throughout the book. The invention is not limited therefore to a construction having both ends thickened.

I desire to point out also that there are in use certain types of binders adapted to hold record cards or sheets in overlapped relation wherein the same bulging of the middle part of the series of record sheets occurs, but in which binders it is not necessary and sometimes not desirable that the partition sheet be flexible to any substantial extent, if at all, in up and down lines parallel with the inner edge as 13. In such case the device of Figs. 3 and 4 may be of substantially hard-rolled, pressed or otherwise formed material of such characteristics as would render the upper and lower end portions 30 and 31 substantially inflexible under the conditions of ordinary use, and the same would apply to the device described in the paragraph next hereinabove as having but one end thickened. The invention is therefore not limited to a device having the substantial amount of flexibility on up and down lines as contemplated by the preferred construction.

I contemplate as being included in these improvements all such changes, variations and departures from what is thus specifically illustrated and described as fall within the scope of the appended claims.

I claim:

1. A partition sheet for loose-leaf binders of the character described, said sheet being substantially rectangular in face view and having a top edge, a bottom edge, an inner side edge and an outer side edge defining the substantially rectangular shape, the sheet having means at its inner side edge portion for holding the sheet in a binder, said sheet being of integral construction and of flexible material, said material being substantially thin at the middle portion thereof substantially from one side edge to the other side edge and being substantially thick at upper and lower portions thereof respectively, said substantially thick portions respectively having substantially plane surfaces and having recesses therein extending from the top and bottom edges respectively toward the middle portion of the sheet.

2. The combination of claim 1 hereof in which said sheet gradually increases in thickness from the middle portion toward the top

and bottom edges respectively and is of fibrous material.

3. The combination of claim 1 hereof in which the relatively thick upper and lower portions of said sheet have recesses therein extending from the upper and lower edges respectively toward the middle portion of the sheet, said recesses defining a thickness of the sheet at the bottom of the recesses respectively which is greater than that of the middle portion of the sheet.

4. The combination of claim 1 hereof in which said middle portion of the sheet is of substantially uniform thickness and the face thereof is of relatively large extent in the up and down direction, the face of the respective upper and lower relatively thick portions of the sheet being of relatively small extent in the up and down directions.

20 5. The combination of claim 1 hereof in which the upper and lower relatively thick portions of the sheet have recesses therein extending from the top and bottom edges respectively toward and merging into the face area of the middle portion of the sheet, all of said recesses being on one side of the sheet.

6. A partition sheet for loose-leaf binders of the character described, said sheet being substantially rectangular and having an inner side edge and an outer side edge defining the substantially rectangular shape, the sheet having means at the inner side edge portion thereof for holding it in the binder, said sheet being of integral construction and of flexible material and being substantially thin at the middle portion thereof and gradually increasing in thickness from said middle portion, and to a material extent, toward and substantially to an edge of the sheet other than a side edge thereof, with recesses in said substantially thick portions extending in the up-and-down directions of the sheet for the purposes specified.

ALFRED M. MARTIN.
